APPARATUS FOR HANDLING MIXED CONCRETE

Ernesto D. Alessio, Akron, Ohio

Application July 13, 1950, Serial No. 173,556

3 Claims. (Cl. 259—178)

1

This invention relates to the handling of mixed concrete. More particularly, it relates to an improved method for maintaining the concrete in a fluid, pourable condition while transporting it to a construction site where it is to be poured. The invention includes a preferred apparatus for carrying out the method.

Concrete for ordinary construction purposes is commonly prepared at a centrally located plant where the proper proportions of Portland cement, water, and aggregate are carefully measured for each batch. The ingredients may be thoroughly mixed at the plant until the individual particles of aggregate are coated with a paste formed by the cement and water, or the mixing may be accomplished in the vehicle used to transport the material to the construction site. The vehicle is equipped with means to agitate the concrete in transit to prevent it from setting before it is poured. Some vehicles are equipped with means for mixing the concrete as well as agitating the mixed material. Often the agitating means on the vehicle is adapted to be operated at two different speeds, one for mixing and one for agitating the mixed material.

The usual vehicular equipment includes a horizontal cylindrical tank (or tank of other shape) provided with means for rotating it on a horizontal axis. The rotation of the tank mixes the concrete or slowly agitates it after mixing. Such tumbling or other violent agitation is harmful to the concrete because it strips the cement paste from the aggregate, and after setting, concrete which has been thus violently agitated during transportation to the construction site has a lower strength than if it had not been agitated. Stirring is not as harmful as tumbling or the like, and does little or no damage to a thoroughly mixed concrete.

Concrete which has been tumbled in transit solidifies very rapidly. This makes it difficult to handle. Concrete which has been merely stirred in transit does not solidify so rapidly, other conditions being comparable. It is therefore more easily handled.

Heat is liberated as the cement in the concrete is hydrated and as the concrete solidifies. This heating has a tendency to vaporize and drive off a portion of the water not yet combined with the cement. This loss may be compensated for in the water-cement ratio when the mix is prepared, but a certain amount of heat is generated by the tumbling, due to the striking of the aggregates against one another, etc., and this cannot be accurately predicted. As a consequence, it is

impossible to calculate the amount of water which will be lost during tumbling, and there is no way of accurately compensating for it. This in itself is a serious objection to the ordinary method of agitating the concrete while transporting it.

According to this invention the concrete is mixed at a central plant where the necessary water is mixed with the other ingredients. The various ingredients are thoroughly mixed. The mixed concrete is then transferred to a tank or other container on a suitable vehicle, such as a truck. Means is provided for slowly stirring the concrete while it is being transported, without tumbling it. The stirrer merely displaces the various particles of aggregate in the fluid or plastic mass of the concrete mix from time to time so as to prevent the mass from solidifying. The preferred stirrer reciprocates slowly back and forth through the plastic mass. This stirring action continues from the time the vehicle is loaded until the concrete is ready to be poured. It has no appreciable effect upon the temperature of the concrete or the amount of water vaporized from it.

The preferred stirrer of this invention may be readily installed on any vehicle equipped with a truck body suitable for hauling liquid. It is readily installed on any conventional dump truck. It includes one or more horizontally disposed stirring bars which are immersed in the concrete and are reciprocated back and forth through the concrete by power means which is preferably driven by the motor or the truck. Preferably, the forward and rear edges of the stirring bars are relatively sharp and the top and bottom surfaces of these bars slope gradually away from both edges. As the bars are moved through the concrete they tend to displace some of the particles of the mix upwardly momentarily, and the particles then sink back of their own accord. This prevents the aggregate from settling toward the bottom of the mix. The stirring is preferably effected with minimum change in the composition of the material on the surface of the concrete. The movement of the particles of the aggregate is slight, but sufficient to prevent the batch from solidifying.

The improved method and the preferred apparatus will be further described with reference to the drawings, in which—

Fig. 1 is a side elevation of a dump truck body with the preferred apparatus installed thereon;

Figs. 2 and 3 are cross-sectional detail views of

portions of the apparatus taken on the lines 2—2 and 3—3, respectively, of Fig. 1;

Fig. 4 is a cross-sectional view taken on the line 4—4 of Fig. 2 showing the cross-sectional shape of the preferred type stirring bars;

Fig. 5 is a cross-sectional view taken on the line 5—5 of Fig. 1; and

Fig. 6 is an enlarged detail view of preferred power means for operating the apparatus.

A preferred stirrer for a standard size dump truck is illustrated in the drawings. The stirring element for the equipment shown includes the three bars 1, 2 and 3. These stirring bars are disposed horizontally with one spaced vertically above the other. They are supported at their ends by the vertical uprights 4, 4. Reinforcing rods 5 are fastened vertically between the stirring bars, as shown in Fig. 2. These rods are preferably formed with a diamond-shaped cross section but they may be round.

Each of the upper stirring bars has a diamond-shaped cross section, as shown in Fig. 4. The forward edge 1 and the rear edge 3 of these bars are sharp, and the top and bottom surfaces 9 taper backwardly from each edge with a fairly low slope. The taper of each sloping portion of the top surface is preferably less than thirty degrees. The lowest stirring bar 3 has a triangular cross section. Its forward and rear edges are sharp and its top surface is tapered similarly to the bars 1 and 2, but the bottom of bar 3 is flat.

The stirring element fits inside the body 10 of the truck so that the stirring bars extend laterally across the body substantially parallel to the bottom of the truck. The uprights 4, 4 are located close to the sides of the truck and the lowest stirring bar 3 is located just above the bottom of the body. The upper ends of the uprights 4 project above the top of the sides of the body somewhat and a bar 12 is welded across the upper ends of these uprights. The portions 13 at each end of the bar 12 project out across the top edge of the sides of the body and a flat plate 15 is welded to each end 13. The plates 15 are relatively wide, as shown in Fig. 1, and they extend vertically downward parallel to the uprights 4 but are along the outside surface of the sides of the truck.

A pair of rollers 18 is mounted on the inside surface of each plate 15 near the corner 19 formed where the plate 15 is welded to the end 13 of the bar 12. The rollers 18 extend inwardly toward the sides of the body. Each pair is adapted to roll in a track 20 located along the top of each side of the body. Each track 20 is preferably a length of channel iron which rests on the outwardly turned flange 22 along the top of the sides of the body and extends from the front to the rear of the body. The channels are positioned with their legs projecting horizontally outwardly to receive the rollers 18 which roll back and forth on the legs when the stirring element is moved through the concrete in the body.

The reciprocating action may be obtained by a variety of different structures. Preferably a fluid pressure cylinder 23 is employed to supply the power required to reciprocate the stirring element. The cylinder 23 is operated from the hydraulic system which normally operates cylinder 24 which raises and lowers the body. Cylinder 23 is pivotally mounted at 28 under the bottom of the body. The outer end of its piston rod 29 is fastened to a crank 30 which is rigidly connected to and projects downwardly from a shaft 32 which extends laterally across the body under its

bottom. As shown in Fig. 5, the crank 30 is located at the center of the shaft and the shaft is supported below the bottom of the body by suitable bearings 35.

The ends 37 of the shaft project outwardly a short distance at each side of the body and a flat bar 38 is rigidly fastened around each end 37 by a key 40. Each bar 38 extends upwardly from the shaft close to its respective side of the body and its upper end is pivotally connected by a rivet 42 to the end of another flat bar 43. The rivet 42, as shown in Fig. 3, extends loosely through the upper end of bar 38 and the abutting end of bar 43, and is held in place by cotter pin 45. Bar 43 slopes downwardly toward the rear of the body and its lower end is pivotally engaged with the downwardly extending plate 15 by a rivet 48 which extends through bar 43 and through a hole 49 (Fig. 2) in plate 15. The rivet is removably fastened in place by cotter pin 50.

Fig. 1 shows the relative position of the bars 38 and 43 in solid lines when the stirring element is at the rear of the body next to the tail gate. The broken lines indicate the relative position of these same bars when the stirring element is shifted to a position near the front end of the body. To move the stirring element from the rear of the body to the forward position shown, fluid is introduced into the cylinder 23 so that its piston rod 29 is retracted into the cylinder. (See Fig. 6.) The movement of rod 29 swings the crank toward the rear of the truck thereby rotating the shaft 32 to swing the bars 38 on each end of the shaft forwardly toward the cab. The movement of the bars 38 shifts the bars 43 forward so that the stirring element is pulled toward the front of the body. Rollers 18 roll along the track 20 as the stirring element is moved. The bars 38 and 43 are swung together in a scissors fashion when the stirrer is at the front of the body.

When the stirrer reaches the front of the body the valve apparatus 55 operates to reverse the flow of fluid into the cylinder 23 so that the piston 29 is forced out of the cylinder and crank 30 is swung forwardly toward the cab. This rotation of shaft 32 swings the bars 38 backwardly so that the bars 43 push the stirring bars toward the rear of the body. While the concrete is being hauled in the truck the stirring bars are constantly reciprocated from one end of the truck body to the other in the manner described.

The hydraulic apparatus for operating the cylinder 23 is not illustrated in detail since such systems are well known. Valve 55 is preferably a solenoid-type valve whose action is controlled by the limit switches 56 shown in Fig. 6. Preferably these switches are positioned so that their followers 58 and 59 roll on the peripheral surface of the hub 58 of crank 30. The studs 60 and 61 are embedded in the surface of hub 58 in the path of the followers. As the crank 30 is swung to its most forward position, stud 60 moves into contact with the follower 58 which closes its switch 56. This energizes the solenoid valve 55 which then operates to cut off the fluid flowing against one side of the piston inside the cylinder 23 and permits the liquid to flow into the cylinder against the opposite side of the piston thereby swinging the crank backward. At the rearmost position of the crank, stud 61 contacts the follower 59 so that the solenoid is again energized and the movement of the piston rod is reversed.

Each of the plates 15 is provided with several

holes such as holes 63 and 64 between the hole 49 and the rollers 18. The pin 48 may be removed from hole 49 and inserted into one of these other holes so that the end of the bar 43 may be fastened at any one of several different positions on plate 15 to vary the point from which the stirring element is pulled. Ordinarily the end of the bar 43 is connected to pull at about the center of the load of concrete so that there is no tendency to tilt the stirrer forward or backward as it moves through the concrete.

Preferably the body will be filled with concrete to a point just above the upper stirring bar so that this bar is moved back and forth through the concrete just below the surface to prevent a crust from forming on the surface. If the stirring element is not completely submerged in the concrete the vertical posts 5 between the bars will prevent a crust from forming on the surface.

The stirring element is moved back and forth through the load of concrete with a slow, regular reciprocating motion. As it moves forward the sharp forward edge 7 of each stirring bar plows through the concrete. The upper tapered surfaces 9 displace particles of aggregate, etc. in the concrete upwardly and prevent their settling to the bottom. On the backward movement the edges 8 and the tapering surfaces 9 above them produce the same effect.

This stirring action is considerably different from the conventional tumbling agitating movement. There is no grinding or pulverizing of the aggregate which tends to strip the paste coating from the aggregate. The concrete may be stirred for considerable periods without becoming over-mixed. This prevents the segregation of the components of the concrete and the concrete is maintained at the desired plasticity until it is ready to be poured into the forms at the construction site.

Concrete mixtures differ from one locality to another depending upon whether the aggregates are smooth or sharp edged, and experts even recommend different mixtures using the same aggregate. Applicant is therefore not to be limited to any particular mixture, but suggests as illustrative a 1-2-4 mixture, meaning a mixture in which the weights of Portland cement, sand and aggregate are used in the ratio of 1:2:4. The water used will vary depending upon various factors, including the amount of moisture in the sand and aggregate. One may use, for instance, about 24 gallons of water, more or less, per yard of dry mixture.

After thorough mixing in a standard mixer, the composition is transferred to a truck equipped with a stirring element of the type illustrated in the drawings. The inside dimensions of the body 10 of the truck are about 6½ feet wide by 10 feet long and 24 to 30 inches high. This will hold about four to five yards of the mixture. The bottom bar is about 1¼ inches above the bottom of the body of the truck, but this distance may be varied, and is preferably only slightly farther from the bottom of the truck than the greatest distance through the aggregate. The stirring element is moved back and forth at the rate of one complete cycle in about two minutes. This speed is preferably variable so that it can be increased for longer and heavier hauls. The stirring element may be designed so that the lower bar is adjustable to a position close to the bottom of the body or to a position further above

the bottom to accommodate different sizes of aggregate. The bars above the bottom bar may also be designed to be tilted forwardly and backwardly. A suitable water tank may also be provided with this equipment. The tank may be installed on the truck at a convenient location so that water may be added to a mixture from time to time as it may be required. This supply of water is also useful for rinsing out the body after a load of concrete is emptied.

The concrete mixture can be dumped from the truck at the construction site by raising one end of the truck body. The amount of water should not be so great as to give a slump of more than two inches when the mix is dumped at the construction site. A slump of one to one and one-half inches is preferred. Slump is measured according to A. S. T. M. designation C 143-39.

The preferred equipment is simple, easily fabricated, and is easily installed on the body of a conventional truck or dump truck. It may also be installed on railroad gondola cars and other vehicles. The parts are easily replaceable and no precision work is required. The equipment is considerably more economical than the very expensive rotary agitators for which special trucks are built. A further advantage in this equipment is that it does not limit the use of the truck on which it is installed to the sole purpose of hauling concrete because when the agitating element is in its forward position against the front of the body the truck may be used to haul dirt, tile, etc.

The term Portland cement is used herein to include fast-setting modifications of the original type of Portland cement.

The apparatus is not limited to the particular design disclosed. The invention is defined in the claims.

What I claim is:

1. In combination with a truck body capable of containing liquid concrete, a track fastened along each side of the body, rollers to roll on said tracks, upright members supported by the rollers and located in the body and close to the two sides thereof, and stirring means which is supported by the uprights and extends substantially from one side of the body to the other and close to the bottom of the body from one side thereof to the other as well as a substantial distance above the bottom; and driving means for reciprocating the rollers, upright members and stirring means from one end of the tracks to the other.

2. The combination of claim 1 which includes downward extensions outside of the truck body from the respective upright members, drive means connecting the same to a shaft located below the body of the truck, a fluid pressure cylinder and drive means connecting the cylinder with the shaft for turning the shaft first in one direction and then in the other as the plunger of the cylinder moves in and out thereof, thereby moving the stirring means back and forth in the truck body by means of said first-mentioned drive means.

3. In combination with an open rectangular truck body capable of containing liquid concrete, a track fastened along each side of the outside of the body and extending substantially from one end thereof to the other, rollers supported on the respective tracks, upright members in the truck body and located close to the sides thereof, said upright members being supported

from the rollers, a plurality of narrow stirring bars disposed horizontally inside the body and spaced one above the other, with the top bar considerably below the top edge of the truck body and the bottom bar close to the bottom of the inside of the body, said bars being fastened to the uprights, power means for moving the rollers, uprights and bars back and forth along the tracks, and driving means connecting the same with the power means.
